UNITED STATES PATENT OFFICE

120,338

DESIGN FOR AN ADVERTISING SIGN

Theodore L. Chryst, Birmingham, Mich.

Application November 13, 1939, Serial No. 88,229

Term of patent 3½ years

To all whom it may concern:

Be it known that I, Theodore L. Chryst, a citizen of the United States, residing at Birmingham, county of Oakland, in the State of Michigan, have invented a new, original, and ornamental Design for an Advertising Sign, of which the following is a specification, reference being made to the accompanying drawing, forming part thereof.

The drawing is a perspective view of an advertising sign, showing my new design.

The rear portion of the design is substantially plain.

I claim:

The ornamental design for an advertising sign, as shown and described.

THEODORE L. CHRYST.
